RECEIVING SYSTEM

Harold F. Elliott, Palo Alto, Calif.

Application June 11, 1932, Serial No. 616,586

8 Claims. (Cl. 250—20)

This invention relates to receiving systems embodying electronic tubes for amplifying, detecting and controlling signals transmitted by carrier waves, and particularly to systems incorporating provisions for automatic control of the amplification.

An object of my invention is the provision of methods and means whereby the functions of amplification and detection are accomplished more effectively and more simply than by the methods heretofore available. Another object is to provide means of detection and amplification whereby the quality of reproduction is improved. Another object is to extend the range of automatic control of amplification. Another object is to accomplish the functions of rectification, amplification and automatic control in a single tube, thereby reducing the number of tubes required and thereby reducing the size and cost of the equipment needed for radio reception and other purposes.

Referring to the drawings:

Figs. 1, 2 and 3 show in outline the arrangement of elements in specially constructed tubes which are suitable for carrying out the objects of my invention. The novel features of these are described and claimed in my co-pending application, Serial No. 605,186, filed April 14, 1932.

Fig. 4 shows circuits of a complete broadcast receiver of the tuned radio frequency type in which the objects of my invention are carried out utilizing the tube shown in Fig. 1.

Fig. 5 shows circuits whereby the tube of Fig. 1 may be used in another manner.

Fig. 6 shows still another circuit arrangement, in this case utilizing tubes of the type shown in Figs. 2 and 3.

Referring to Fig. 1, numeral 1 designates a glass envelope for the tube. Numeral 2 designates a cathode which may be of the uni-potential type. Numeral 3 designates a connection to the cathode which may be brought out to a terminal on the base of the tube. Numerals 5—5 designate terminals for a heater 4 within the cathode. Numeral 6 designates an anode and numeral 7 the terminal for the same brought out to a connection on the base. Numerals 8 and 9 designate two control grids symmetrically arranged in the space between the cathode and the anode. For the sake of clarity, one of these grids, as 8, is shown in full lines, and the other, as 9, is shown in dotted lines. Numerals 10 and 11 designate terminals for the two grids 8 and 9 respectively. Numeral 12 designates an auxiliary anode placed around an extended portion of the cathode, and numeral

13 shows an external terminal connection for the auxiliary anode.

Fig. 2 shows a second specially constructed tube also suitable for carrying out the objects of the invention. This tube is similar to that of Fig. 1 except that an additional electrode in the form of a screen grid 14 is placed between the control grids 8—9 and the main anode 6. A connection for the screen is shown at 15.

Fig. 3 shows a third specially constructed tube likewise suitable for carrying out the objects of the invention. This tube is similar to that of Fig. 2 except that an additional screen electrode 16 is added between the screen grid 14 and the anode 6. This added screen, 15, may serve as a suppressor grid to minimize the effects of secondary emission as is now well understood in connection with the so-called "pentode" tubes now in commercial use. The suppressor grid may be connected directly to the cathode within the tube or a connection 17 may be brought out to an external terminal.

Referring to Fig. 4, numerals 18 and 19 designate amplifier tubes which serve to amplify the incoming signals. Numeral 20 designates a detector tube, and numeral 21 an audio amplifier or power output tube. Tube 22 is a rectifier which, together with the filter comprising capacitors 23, 24 and 25 and reactors 26 and 27, serve to supply direct current potentials of a few hundred volts for the operation of the receiver. Inasmuch as the functions and the connections of all of the tubes except the detector 20 are closely in accordance with standard practice in commercial broadcast receivers now in wide use, only the connections and functions of tube 20 will be described in detail. The elements of tube 20 should preferably be arranged substantially in accordance with Fig. 1 or 2, to which reference has already been made. If the structure shown in Fig. 1 is used, then the screen grid 14, resistor 28 and by-pass capacitor 29 may be omitted from the circuit shown in Fig. 4, otherwise the description which follows is applicable to both the tube of Fig. 1 and the tube of Fig. 2. The principal difference between the two is that the use of the screen enables the tube of Fig. 2 to give somewhat higher audio amplification than the tube of Fig. 1 which is sometimes advantageous when very high sensitivity is desired.

In Fig. 4 the amplified signals delivered by tube 19 are applied to the two grids 8 and 9 of tube 20 in phase opposition. This is accomplished by arranging the circuit which interlinks the two tubes 19 and 20 so that point 34, in this interlink-

ing circuit, is substantially at ground potential insofar as the radio frequency currents circulating in this circuit are concerned. This condition arises from the fact that point 34 is a potential 5 nodal point in the interlinking circuit which comprises two resonant circuits 30—31, and 32—33, which are connected in series in so far as radio frequency currents are concerned. Circuit 10 30—31 is tuned to the frequency to be received, as is also circuit 32—33. The circuits are joined 15 in series at point 34, which is thus a potential nodal point for radio frequency currents and is above ground potential only by the amount of the in-phase potential required to make up the 20 energy losses associated with circuit 32—33. It will be noted that point 34 is not grounded, but is isolated from ground by resistor 37 having several hundred thousand ohms resistance as outlined below. Thus it will be seen that point 34 25 is not grounded, but being a nodal point, is actually at substantially ground potential. Radio frequency currents in the interlinking circuit flow in series through capacitor 31, inductor 39, inductor 32 and capacitor 33. It will be noted 30 that the two tuning capacitors 31 and 33, of this interlinking circuit, each has one of its electrodes grounded. This makes it possible to construct these two capacitors, together with capacitors 35 and 36 which tune the input circuits of tubes 18 and 19, as a single unit with common rotor, in accordance with standard practice in broadcast receivers. The two grids 8 and 9 of tube 20 35 are shown as connected to taps on coils 30 and 32. The locations of these taps should preferably be chosen so that the potentials applied to grids 8 and 9 are substantially equal and opposite in phase, and of a value which gives maximum response from tube 20 without imposing too heavy a load upon the circuits to which the 40 grids are connected. In the arrangement shown in Fig. 4, the cathode 2 of tube 20 is grounded and point 34 in the interlinking circuit is connected to ground and thence to the cathode through load resistor 37, sometimes called a grid 45 leak. Resistor 37, which is preferably of the order of a few hundred thousand ohms, may be shunted by the capacitor 38, of the order of 50 to 100 micro-microfarads. Alternately capacitor 38 may be omitted if the stray capacitances of 50 the system are sufficient to maintain balanced input potentials for grids 8 and 9.

In operation the two grids 8 and 9, together with the cathode 2, act as a full wave rectifier for the radio frequency potentials which are applied to the two grids. The process of rectification results in a pulsating direct current across resistor 37. These pulsations correspond to the modulations of the incoming signals and are applied to the two grids 8 and 9 in parallel. 55 Tube 20 therefore acts as an audio-frequency amplifier for the rectified signals. The amplified output of tube 20 may be applied directly to a translating device or further amplified in tube 21, as shown in Fig. 4. Any suitable form of coupling arrangement may be used between tube 20 and tube 21; in Fig. 4 resistance-capacitance coupling is shown. Resistor 39 is preferably of the order of 100,000 ohms; capacitor 40 of the order of .05 microfarad; resistor 41 is preferably 60 a potentiometer having a total resistance of about $\frac{1}{2}$ megohm and serves to control the input to tube 21, and consequently the output from speaker following the latter.

The negative potentials which accumulate on 75 the grids 8 and 9 during the process of rectifica-

tion appear at point 34 and may be used automatically to control the amplification in tubes 18 and 19. The automatic volume control circuits through which this is carried out are shown in Fig. 4 as comprising resistors 42, 45 and 47, together with by-pass capacitors 43, 46 and 48. The resistors may be of the order of $\frac{1}{2}$ to 2 megohms and the by-pass capacitors of the order of .05 to .1 microfarad. Since this arrangement is in accordance with commercial practice 10 in broadcast receivers having automatic volume control, further details are unnecessary here.

In cases where it is desired to maintain a very close balance in the potentials applied to grids 8 and 9 of tube 20, capacitor 64 and inductor 65 15 may be connected as shown to balance the effect of capacitor 66 and inductor 67. Inductor 65 may be shunted by a network simulating the effect of tube 19 on inductor 67 if desired.

Referring now to Fig. 5, circuits are shown 20 whereby the range of the automatic volume control system may be extended, and also whereby the governing action of the automatic control may be caused to take effect when the signals reach a predetermined level. With this arrangement, signals below this level are not affected by the automatic control and there is, consequently, no attenuation of weak signals. The circuits of Fig. 5 are similar to those of Fig. 4 except that the load resistor 37 is connected directly between point 34 and cathode 2, and the latter instead of being grounded is connected through resistors 49—50 to a point in the power supply system which is negative with respect to ground. This negative potential should preferably be of the order of 100 volts and may, if convenient, be obtained by connecting point 56 to the negative side of the speaker field. Capacitors 51, 52 and 53 serve to prevent pulsations in the power supply system from circulating in 40 the circuits of tube 20. In the circuits shown in Fig. 5, the plate circuit of tube 20 is shown as including an auto-transformer 54, the output of which may be coupled to a succeeding tube by means of coupling capacitor 40 and potentiometer 41, as in Fig. 4. Alternately a standard transformer or resistance coupling may be used in place of the auto-transformer. In order to obtain the full benefit of the connections of Fig. 5, the positive potential applied to point 55 and 50 the negative potential applied to point 56 should be adjusted so that, in the absence of signals, cathode 2 is positive with respect to ground by a potential of 10 to 30 volts. When signals are received, the space current in tube 20 is reduced and the drop across resistors 49 and 50 is consequently reduced. Cathode 2 then more 55 nearly approaches the negative potential of point 56. When signals of sufficient strength are received to cause cathode 2 to become negative 60 with respect to ground, electrons will be attracted from the cathode to the auxiliary anode 12, thereby causing current to flow through resistor 57 and causing point 58 to become negative 65 with respect to ground. This negative potential at point 58 may be used for automatic volume control by connecting point 58 to the grid circuits of the preceding tubes, as through resistor 42, by-pass capacitor 43 and bus 44, which may be arranged as shown in Fig. 4.

Another arrangement whereby tubes of the type shown in the Figs. 1, 2 and 3 may be used to perform the functions of rectification, audio amplification and automatic volume control is shown in Fig. 6. In this arrangement the aux- 75

illary anode 12, together with the cathode 2, serve as a half wave rectifier whereby the amplified radio frequency signals are converted into pulsating direct currents in resistor 37. The 5 audio frequency components of these pulsations may be applied to the two grids 8 and 9, or to either one of these, through the medium of filter resistor 59, by-pass capacitors 60 and 61 and potentiometer 62. The direct current component 10 of the potentials across resistor 37 may be applied for automatic volume control by connecting resistor 42 and capacitor 43 to point 63 and connecting the grid circuits of the amplifier tubes to bus 44, as in Fig. 4. Biasing potentials for the 15 grids 8 and 9 may be applied to potentiometer 62 in the same manner as is shown for potentiometer 61 in Fig. 4, or, alternatively, the bias obtained from the rectified signals as is the case 20 for tube 20 in Figures 4 and 5.

20 If amplifier tubes of the present multi-mu type are employed at 18 and 19, Fig. 4, the sensitivity of the receiver may be controlled by adjusting the potentials applied to the electrodes of these tubes in any of the customary ways, as 25 by the potentiometer 68, 69, 70 shown in Fig. 4. This feature may conveniently be retained for adjusting the amount of gain preceding the detector and consequently the extent to which the receiver will respond to incoming signals and 30 atmospheric disturbances.

While the circuits shown herein have all been directed especially to tuned radio frequency receivers having one side of the tuning condensers grounded, it will be evident to those familiar with 35 radio receivers that the circuits may also be applied to instruments of the superheterodyne type, and that many variations in circuit arrangements and tube construction are possible. My invention is not limited to the arrangement shown, 40 but is best defined in the appended claims.

What I claim is:

1. Amplifying and detecting apparatus embodying two discrete resonant circuits connected in series with tuning capacitors having two electrodes 45 maintained at a common potential, an electron tube having a cathode and two grids symmetrically placed in the electron stream and having equal effect thereon, connections to the two grids from points of equal and opposite potentials in 50 said resonant circuits, a connection including an impedance from an electrical center point in the circuits to said cathode and a connection including an impedance from said center to gain control means in the amplifier.

55 2. Signal amplifying and detecting apparatus embodying resonant circuits with tuning capacitors having a plurality of electrodes maintained at a common potential, an electron tube having a cathode and two grids symmetrically located 60 in the electron stream and having equal effect thereon, an input circuit for the tube comprising an inductor tuned by two of the capacitors in series, connections from the grids to points on the inductor whereby equal signal potentials may 65 be applied to the two grids in phase opposition, connections including an impedance from the electrical center of the inductor to said cathode, and means whereby rectified signal potentials associated with the impedance may be utilized 70 for automatic control of amplification.

3. Carrier wave amplifying and detecting apparatus comprising an amplifier and a detector having resonant circuits with a plurality of tuning capacitors one side of each of which is

grounded, an electron tube having a cathode, an anode, and two grids symmetrically located in the electron stream and having equal effect thereon, an electrically symmetrical input circuit comprising two of the tuning capacitors with an inductor and the two grids, connections including an impedance from the electrical center of the inductor to the cathode, and the connections including an impedance from said center to control means in the amplifying apparatus. 10

4. A carrier wave amplifier and detector comprising a plurality of tuning capacitors one side of each of which is grounded, an electron tube having a cathode, an anode, two grids symmetrically located in the electron stream and having equal effect thereon, and an auxiliary anode, an electrically symmetrical input circuit comprising two of the tuning capacitors with an inductor as well as the two grids and an impedance in a circuit between the grids and cathode, an output 20 circuit comprising the cathode, anode, an impedance and a source of potential, and a volume control circuit including the source of potential, the cathode, the auxiliary anode and control means in the amplifier whereby said tube serves 25 to rectify and amplify signals applied thereto, and to control the amplification of preceding tubes respecting signals above a predetermined level only. 30

5. A detector governor comprising an electronic tube having a cathode and two cold electrodes symmetrically related to the cathode, an electrically symmetrical carrier current input circuit having connections at potential nodal points, connections for maintaining one nodal point at cathode potential for carrier currents, connections from the cold electrodes to electrically symmetrical antinodal points, and connections including impedances from the second nodal 35 point to the cathode and to a governor circuit. 40

6. The method of carrier wave detection and automatic gain control in a radio circuit having a carrier wave input, detector, electrically symmetrical resonant circuits, and a carrier wave nodal point intermediate of said resonant circuits; which comprises balancing the carrier wave input to the detector in the resonant circuits, balancing the reaction of the carrier wave within the detector, and deriving potentials for 45 automatic control from said carrier wave nodal point. 50

7. The method of carrier wave detection and automatic gain control in a radio circuit having a carrier wave input, detector, two electrically symmetrical resonant circuits, and a carrier wave nodal point between said two resonant circuits; which comprises balancing the carrier wave input to the detector in the two said resonant circuits, balancing the reaction of the carrier wave within the detector, and deriving potentials for 55 automatic control from said carrier wave nodal point. 60

8. The method of carrier wave detection and automatic gain control in a radio circuit having a carrier wave input, detector, electrically symmetrical resonant circuits, and a carrier wave nodal point intermediate of said resonant circuits; which comprises introducing the carrier wave in series through the resonant circuits, balancing the carrier wave input to the detector in the resonant circuits, balancing the reaction of the carrier wave within the detector, and establishing a nodal point automatic control potential. 70

HAROLD F. ELLIOTT.
